UNITED STATES PATENT OFFICE.

THOMAS NELSON EVENS, OF LONDON, ENGLAND.

MEANS FOR SETTING UP LOOSE-LETTER SIGNS AND NOTICE BOARDS.

1,413,266.

Specification of Letters Patent. Patented Apr. 18, 1922.

Application filed February 2, 1922. Serial No. 533,630.

To all whom it may concern:

Be it known that I, THOMAS NELSON EVENS, a citizen of the United Kingdom of Great Britain and Ireland, and resident of 5 3 and 4 Eagle Street, London, W. C. 1, England, have invented certain new and useful Improvements in Means for Setting up Loose-Letter Signs and Notice Boards, of which the following is a specification, such 10 as will enable others skilled in the art to which it appertains to make and use the same.

This invention relates to signs and notice boards of the kind with which loose letters, 15 figures, symbols and the like and which I will call characters, are used and refers more particularly to an improved method of storing and of discharging from the store the required characters to make up the sign 20 or notice required.

The invention may also include novel means for introducing in the sequence required the characters to the board or base upon which they are to be mounted.

25 Briefly the invention consists in storing like characters in groove-like cases or holders from one end or part of which they can be discharged out one at a time from the said cases or holders into any suitable receptacle or if preferred to means by which 30 they are introduced directly or indirectly into the grooves in the board or base upon which they are to be assembled.

The method of introduction to the board 35 or base may be as desired such as by bringing the groove-like case into alignment with the individual grooves in the board or by connecting a number of the cases or holders to one common outlet placed opposite the groove in the board into which groove the characters will enter by gravity or by being 40 mechanically, pneumatically or hand pushed the said outlet or the board being moved along step by step as each line is completed.

45 Suitable margin-making and spacing devices, such as that shown in Fig. 7 of the drawings accompanying the specification of my application for United States Letters Patent No. 401210, can be used in like manner as that employed for the characters.

In another form a number of groove-like cases may be arranged on one rotatable holder which can be turned as required to bring the selected character opposite the 50 groove in the board or base.

I will now describe my invention with reference to the accompanying drawings of which the main figure is largely diagrammatic for the reason that the invention can be carried out in many ways. 60

Fig. 1 is a diagrammatic view illustrating the making up of a sign through the improved device.

Fig. 2 is a sectional detail of the manually operable members, whereby the letters are 65 successively released.

Figs. 3 and 4 are details in elevation, showing respectively the letter retaining means in holding and releasing positions.

In Fig. 1, are arranged lines 1, which represent the grooves or holders in which the characters are stored it being understood that any suitable number of these may be employed, such as twenty-six for the letters of the alphabet, ten for numbers, and perhaps a dozen for &, punctuation characters and the like. 70

The drawing shows the letters A, B, Y and Z mounted sidewardly in these holders and it will be understood the remaining 80 holders are arranged between those holding A and B and those holding Y and Z or as may be convenient. Each of these holders 1 has its continuation or slide 2 adapted to receive the letters said slides terminating 85 at a common chute 3 which registers one at a time with the grooves 4 in the board or base 5 which is shown side uppermost and in two of the grooves of which some letters have been positioned. The board is held in 90 a frame α adapted to be moved with the board to bring the grooves 4 one at a time into register with the chute 3.

In these drawings I have arranged for the discharge to be by gravity and in Figs. 95 2, 3 and 4 I show how the characters can be released. Figs. 3 and 4 show two views of the end of one of the holders 1 seen in Fig. 1 and in which the letter W is held. It is to be understood that these characters are 100 placed in the holders one over the other and are adapted to slide, by gravity, in the present case, to the common chute and thence to the board.

For the purpose of holding and releasing, 105 one at a time, the letters seen in Fig. 4, I provide a spring controlled side plate 6 pivoted at 7 and having a return end 8 adapted, normally, to close the outlet from the holder as is seen in Fig. 3. I also provide a finger 110

9 on the plate to prevent two characters falling out at the one operation. This finger simply passes between the two lowermost characters when the under one is being released and holds the second in place until the end of the holder is re-covered by the part 8 when all the letters in the holder drop down one step or stage.

For the purpose of actuating the spring controlled plates I provide a key board, of which two keys *a*, *a* are seen in Fig. 2, having characters corresponding to those in the holders and each is provided with a Bowden wire 10 actuated through a cranked lever 15 11 and connected at 12 to the spring plate in such a manner that when a key is depressed it actuates the wire, moves the spring plate to the position seen in Fig. 4, thus allowing one character to fall out and brings the finger under the next character until the pull of the wire is released when the parts re-assume the position seen in Fig. 3.

What I claim is:—

In combination, a series of letter holders having open discharge ends, a slide plate 25 pivotally connected to each holder and having a return end adapted to normally underlie the discharge end of the holder to prevent discharge of the letters, said plate having a finger adapted to normally rest beyond the letters in the holder and to be positioned intermediate certain of the letters in the holder in the operative movement of the slide plate, a spring for holding the slide plate in normal position, and means to operate the slide plate against the tension of the spring.

In witness whereof I have hereunto set my hand in presence of two witnesses.

THOMAS NELSON EVENS.
